A. G. KUPETZ

COMBINED TYPEWRITING AND COMPUTING MACHINE

Filed August 23, 1924

UNITED STATES PATENT OFFICE.

ADOLPH G. KUPETZ, OF NEW ROCHELLE, NEW YORK, ASSIGNOR TO UNDERWOOD COMPUTING MACHINE COMPANY, OF NEW YORK, N. Y., A CORPORATION OF NEW YORK.

COMBINED TYPEWRITING AND COMPUTING MACHINE.

Application filed August 23, 1924. Serial No. 733,693.

To all whom it may concern:

Be it known that I, ADOLPH G. KUPETZ, a citizen of the United States, residing in New Rochelle, in the county of Westchester and

5 State of New York, have invented certain new and useful Improvements in Combined Typewriting and Computing Machines, of which the following is a specification.

This invention relates to combined computing and typewriting machines, and more particularly to an improvement in the type-driving mechanism for a machine of this character, such that typing of the numbers, which are set up to be run into the wheels 10 of the register of the machine, will be assured, and that any tendency to print a light or partial impression of the type or failure to print the same will be entirely overcome.

In machines of this nature, the typewriting mechanism is positioned above the computing mechanism, and the digit-keys of the typing mechanism operate indexing devices associated with a computing bar, forming a portion of the adding machine, and 15 cause a numeral-printing type to be driven against a work-sheet, after which a general operator is used for running the number into the dial-wheels of the register. The indexing devices usually comprise a set of pins, 20 each digit-key being capable of setting a pin in any denomination, and it is the practice to adjust the mechanism of the machine so as to insure setting of the pin on the computing bar before the type strikes the platen to print. It has been found in practice with this arrangement that the numeral pins are usually set up, but not infrequently the type-bars fail to reach the platen to 25 print the necessary numeral. The operator, upon noting the absence of the numeral on the work-sheet, is apt to strike the key again and thereby cause an error in the calculating 30 operation.

It is, therefore, a feature of the present invention to overcome this disadvantage by providing a sub-lever, which is pivoted to the key-lever and linked by means of the usual bell-crank to the type-bars. The key-lever operates to impart an initial throw to the sub-lever, and after the movement of the key-lever has been arrested, the sub-lever continues to travel by its own momentum against the action of suitable resilient 35 means to reach the platen, with sufficient

force, to cause the type to be properly impressed upon the work-sheet. 55

Other features and advantages will hereinafter appear.

In the accompanying drawings,

Figure 1 is a side elevation of a portion of 60 a combined computing and typewriting machine with the invention applied thereto and showing a type-bar and printing key in normal position.

Figure 2 is a view similar to Figure 1, but 65 showing the position of a type-bar and associated parts of the machine upon an initial depression, and arrest of a printing key, one of the indexing pins being shown depressed.

Figure 3 shows the position of a type-bar 70 and type after being driven against the platen by the momentum of a sub-lever.

Figure 4 is a view of a key-lever and sub-lever disassembled for clearness of illustration. 75

Figure 5 is a view representing the application of the present invention to all of the keys of an ordinary typewriting machine.

From each of the keys 12 depends a stem 80 13, which, when depressed, engages at its lower end, an arm 14 on a rock-shaft 15, there being one rock-shaft for each key 12. These rock-shafts 15 individually rock linkages 16, which are connected to arms 17 on the rock-shafts. Lower links or digit-bars 18 are also connected through linkages 16 to the arms 17 and are depressed thereby for the purpose of depressing indexing pins 19, the latter being mounted in forwardly and rearwardly extending denominational pin-bars 20. After a number is typed 85 and its corresponding number pins are set, a general operator 21 is actuated by a suitable handle or power means (not shown) and engages the depressed pins 19, and then, by means of racks 22 on the forward ends of pin-bars 20 meshing with suitable pinions (not shown) fixed to registers 23, the number is run into the dial-wheels of the 90 register. 95

The foregoing description is of mechanism which has heretofore been used in combined computing and typewriting machines, and its description here is given simply for a clear understanding of the manner in which 100 the present invention, now to be described, is associated therewith. 105

The present invention concerns a sub-lever

- 24 which is pivoted at 25 to the key-lever 10, the sub-lever lying flat against the key-lever throughout its length, and following the general contour of the key-lever 10.
- 5 The sub-lever 24 carries a stud 25' which engages a fork 26 of a bell-crank lever 27 to rock the same about a pivot 28, and thereby swing a type-bar 29 upwardly and rearwardly about a pivot 30, to cause type 31
- 10 to print against a platen 32. An ear 33', formed upon the under side of the sub-lever 24, adjacent the pivot 25, engages the end of a return spring 33, which normally holds the free end 34 of the said lever upwardly
- 15 against a stop 36, forming the upper wall of a rectangular collar 37, enclosing said free end and carried by the key-lever 10. The collar acts as a guide for the sub-lever 24 and also as a means for limiting the free
- 20 angular movement of the sub-lever 24 with respect to the key-lever 10. It will be noted, that the outer wall of the collar 37 is disposed parallel with the side of the lever 10 and is sufficiently spaced therefrom to permit
- 25 movement of the free end of the sub-lever 24 therewithin, the lower portion of the collar forming a stop 38 to limit the downward throw of the sub-lever. The free end 34 of the sub-lever is cut away, as indicated at 39, so as to permit a proper amount of movement of the same within the collar 37, and a weight 40 may be attached to the outer end of the sub-lever, the function of which will be later described. Upon striking the key 12 to rock key-lever 10 about its pivot 11, the stop 36, against which the free end 34 of the sub-lever 24 normally rests, will cause the sub-lever to move bodily with the key-lever. During this movement,
- 30 the stem 13 has been depressed to actuate the corresponding rock-shaft 15, and thereby effect the setting of an indexing pin 19 of the computing mechanism (see Figure 2), the downward movement of the stem 13 being
- 35 arrested as the pin is set. The motion thus initially imparted to the sub-lever 24 will cause the same to continue its movement beyond this point by its own momentum and swing about its pivot a sufficient distance to cause
- 40 the type to reach the platen to print the numeral, as illustrated in Figure 3, and the inertia of the weight 40 aids the sub-lever to properly actuate the printing elements. The key-lever 12 when released will be returned
- 45 to its normal position by the spring 33, which causes the free end 34 of the sub-lever to press upwardly against the stop 36 of the collar 37, thus both the key-lever and sub-lever return to normal position as a unit.
- 50 Any suitable means for vertically adjusting the stem 13 may be provided, and in the present application is shown as a yoke 41 pivoted at 42 upon the key-lever 10, and, through the medium of set-screws 43, adjustable against the forward edge of the

key-lever, the yoke may be moved about its pivot. The stem 13 is pivoted to the yoke at a point 44 disposed horizontally to the pivot 42, so that, when the yoke 41 is moved, the stem 13 is adjusted vertically to with respect to the arm 14 of the rock-shaft 15, and by this means the relationship of the computing mechanism and printing elements may be properly adjusted.

Variations may be resorted to within the scope of the invention, and portions of the improvements may be used without others.

Having thus described my invention, I claim:

1. In a combined typewriting and computing machine, the combination of indexing mechanism including numeral-key-levers arrested at the completion of their indexing strokes, a set of numeral-type-bar-operating levers operable by said indexing levers, and a platen, said type-operating levers and the type-bars movable independently of the indexing keys after the arrest of the latter, whereby the type-bars subsequently continue in motion and strike against the platen. 90

2. In a combined typewriting and computing machine, the combination of indexing mechanism including numeral-key-levers arrested at the completion of their indexing strokes, a set of numeral-type-bar-operating levers operable by said indexing levers, and a platen, said type-operating levers and the type-bars movable independently of the indexing keys after the arrest of the latter, whereby the type-bars subsequently continue in motion and strike against the platen, a lost-motion connection being provided between said indexing key-levers and said type-bar-operating levers to permit such independent motion. 100

3. In a combined typewriting and computing machine, the combination of indexing mechanism including numeral-key-levers arrested at the completion of their indexing strokes, a set of numeral-type-bar-operating levers operable by said indexing levers, and a platen, said type-operating levers and the type-bars movable independently of the indexing keys after the arrest of the latter, whereby the type-bars subsequently continue in motion and strike against the platen, a lost-motion connection being provided between said indexing key-levers and said type-bar-operating levers to permit such independent motion, said type-bar-operating levers lying side by side with the indexing key-levers, and pivoted respectively thereto. 115

4. In a combined typewriting and computing machine, the combination of indexing mechanism including numeral-key-levers arrested at the completion of their indexing strokes, a set of numeral-type-bar-operating levers operable by said indexing levers, a platen, said type-operating levers 125

and the type-bars movable independently of the indexing keys after the arrest of the latter, whereby the type-bars subsequently continue in motion and strike against the platen, a lost-motion connection being provided between said indexing key-levers and said type-bar-operating levers to permit such independent motion, and resilient means for maintaining normal relation between each indexing key-lever and its associated type-operating lever.

5. In a combined typewriting and computing machine, the combination of indexing mechanism including numeral-key-levers arrested at the completion of their indexing strokes, a set of numeral-type-bar-operating levers operable by said indexing levers, and a platen, said type-operating levers and the type-bars movable independently of the indexing keys after the arrest of the latter, whereby the type-bars subsequently continue in motion and strike against the platen, a lost-motion connection being provided between said indexing key-levers and said type-bar-operating levers to permit such independent motion, said indexing key-levers pivoted at their rear ends and each type-bar-operating lever lying compactly alongside of its associated indexing lever and pivoted at its rear end thereto.

15. In a combined typewriting and computing machine, the combination of indexing mechanism including numeral-key-levers arrested at the completion of their indexing strokes, a set of numeral-type-bar-operating levers operable by said indexing levers, and a platen, said type-operating levers and the type-bars movable independently of the indexing keys after the arrest of the latter, whereby the type-bars subsequently continue in motion and strike against the platen, a lost-motion connection being provided between said indexing key-levers and said type-bar-operating levers to permit such independent motion, said indexing key-levers pivoted at their rear ends and each type-bar-operating lever lying compactly alongside of its associated indexing lever and pivoted at its rear end thereto.

25. In a combined typewriting and computing machine, the combination of indexing mechanism including numeral-key-levers arrested at the completion of their indexing strokes, a set of numeral-type-bar-operating levers operable by said indexing levers, and a platen, said type-operating levers and the type-bars movable independently of the indexing keys after the arrest of the latter, whereby the type-bars subsequently continue in motion and strike against the platen, a lost-motion connection being provided between said indexing key-levers and said type-bar-operating levers to permit such independent motion, said indexing key-levers pivoted at their rear ends and each type-bar-operating lever lying compactly alongside of its associated indexing lever and pivoted at its rear end thereto.

35. In a combined typewriting and computing machine, the combination of indexing mechanism including numeral-key-levers arrested at the completion of their indexing strokes, a set of numeral-type-bar-operating levers operable by said indexing levers, and a platen, said type-operating levers and the type-bars movable independently of the indexing keys after the arrest of the latter, whereby the type-bars subsequently continue in motion and strike against the platen, a lost-motion connection being provided between said indexing key-levers and said type-bar-operating levers to permit such independent motion, said indexing key-levers pivoted at their rear ends and each type-bar-operating lever lying compactly alongside of its associated indexing lever and pivoted at its rear end thereto.

40. In a combined typewriting and computing machine, the combination of indexing mechanism including numeral-key-levers arrested at the completion of their indexing strokes, a set of numeral-type-bar-operating levers operable by said indexing levers, and a platen, said type-operating levers and the type-bars movable independently of the indexing keys after the arrest of the latter, whereby the type-bars subsequently continue in motion and strike against the platen, a lost-motion connection being provided between said indexing key-levers and said type-bar-operating levers to permit such independent motion, said indexing key-levers pivoted at their rear ends and each type-bar-operating lever lying compactly alongside of its associated indexing lever and pivoted at its rear end thereto.

platen, a lost-motion connection being provided between said indexing key-levers and said type-bar-operating levers to permit such independent motion, and returning springs connected to said type-operating levers to return the same together with said indexing key-levers.

7. In a combined typewriting and computing machine, the combination of indexing mechanism including numeral-key-levers arrested at the completion of their indexing strokes, a set of numeral-type-bar-operating levers operable by said indexing levers, and a platen, said type-operating levers and the type-bars movable independently of the indexing keys after the arrest of the latter, whereby the type-bars subsequently continue in motion and strike against the platen, yokes being provided upon the indexing key-levers in which the type-operating levers play, and whereby limited relative movement of the indexing key-levers and the type-operating levers is permitted.

8. In a combined typewriting and computing machine, the combination of indexing mechanism including numeral-key-levers arrested at the completion of their indexing strokes, a set of numeral-type-bar-operating levers operable by said indexing levers, and a platen, said type-operating levers and the type-bars movable independently of the indexing keys after the arrest of the latter, whereby the type-bars subsequently continue in motion and strike against the platen, means being provided for effecting relative adjustment between the indexing key-levers and the indexing devices operable thereby, to insure accurate setting of the indexing devices by the keys.

ADOLPH G. KUPETZ.
